Primary Examiner — S. Bryan Reinholdt, Jr.(74) *Attorney, Agent, or Firm* — Haynes and Boone, LLP(57) **CLAIM**

The ornamental design for a cooking utensil, as shown and described.

DESCRIPTION

This application is related to U.S. application Ser. No. 29/727,324, filed Mar. 10, 2020, the entire disclosure of which is hereby incorporated herein by reference.

This application is also related to U.S. application Ser. No. 29/754,352, filed Oct. 9, 2020, the entire disclosure of which is hereby incorporated herein by reference.

This application is also related to U.S. application Ser. No. 29/727,321, filed Mar. 10, 2020, the entire disclosure of which is hereby incorporated herein by reference.

This application is also related to U.S. application Ser. No. 29/754,356, filed Oct. 9, 2020, the entire disclosure of which is hereby incorporated herein by reference.

This application is also related to U.S. application Ser. No. 29/727,308, filed Mar. 10, 2020, the entire disclosure of which is hereby incorporated herein by reference.

FIG. 1 is a front perspective view of a cooking utensil showing our new design according to a first embodiment;

(Continued)

FIG. 2 is a top view of the first embodiment;
FIG. 3 is a bottom view of the first embodiment;
FIG. 4 is a right side view of the first embodiment;
FIG. 5 is a left side view of the first embodiment;
FIG. 6 is a front view of the first embodiment shown at a larger scale;
FIG. 7 is a rear view of the first embodiment shown at a larger scale; and
FIG. 8 is a rear perspective view of the first embodiment; and,
FIG. 9 is a top view of the cooking utensil showing our new design according to a second embodiment.
The broken lines shown in FIGS. 1-9 depict portions of the cooking utensil that form no part of the claimed design.
In FIG. 9, the second embodiment of the cooking utensil is shown with four (4) sets of break lines; neither the break lines nor the appearance of any portion of the second embodiment of the cooking utensil between each set of the break lines forms part of the claimed design.
